AUTOMOBILE DOOR LOCKING STRUCTURE

Edward D. Dall, Detroit, Mich., assignor to Houde-Hershey Corporation, Detroit, Mich., a corporation of Michigan

Application August 17, 1940, Serial No. 353,008

2 Claims. (CL 292—229)

My invention relates to door locking structure adapted particularly for the individual locking of the doors of vehicles such as automobiles. The invention is particularly useful in connection with locks of the rocking latch bolt type in which the latch bolt, when in latching position, is engaged by spring pressed cam or wedge members which tend to keep on rocking the latch bolt until any slack or loose motion of the door is taken up so that the door will be held tightly in closed position against sealing or packing material provided on the seating ledges on the door frame.

A lock structure of this type is disclosed in my copending application, Serial No. 321,150, filed February 28, 1940.

In the lock structure such as disclosed in my copending application, the wedging members, at their front and back edges, engage front and back guide walls which guide the wedge members in their vertical movement for application of their wedging surfaces to the latch bolt. I have found that, while the vehicle is running, and the doors are more or less agitated or vibrated, the wedging members which are urged into wedging engagement by springs, will exert undue pressure against the latch bolt and will tend to become set or stuck by their frictional engagement with the latch bolt and the guide walls so that considerable and unnecessary effort is necessary on the door handles for effecting release of the wedging members for unlatching of the door. Furthermore, such unnecessary wedging force will eventually cause the door to be forced against its seating ledges to exert unnecessary pressure against the sealing material so that the sealing material will lose its elasticity or resiliency and will deteriorate.

The important object of my invention is therefore to provide simple and effective means for preventing such sticking action and to permit the wedging members to be easily released by manipulation of the door handle. I accomplish this by providing resilient backing for the wedging members, preferably springs interposed between the back edges of the wedge members and the back guide walls, so that, while the wedge members are shifted longitudinally to apply wedging action against the latch bolt, the wedging members may move sufficiently transversely, and the wedging action is cushioned without interfering with the efficient wedging of the latch bolt for full closure and sealing of the doors.

On the drawing I have shown a lock structure such as disclosed in my copending application

referred to and have applied thereto the wedging member cushioning means.

On the drawing:

Figure 1 is a front elevation of the lock structure showing the wedging members in wedging engagement with the latch bolt;

Figure 2 is a view similar to Figure 1 but showing the outer wall of the wedging member guide frame cut away;

Figure 3 is an elevation of the keeper on the door jamb and with the latch bolt supporting housing in longitudinal section; and

Figure 4 is an enlarged section on plane IV—IV Figure 1.

The housing for the lock structure comprises the base wall 10 which is secured to the door structure, and the flange wall 11 which extends parallel with the edge of the door. On the outer side of the flange wall 11 is secured the oblong-shaped housing 12 for the rocking latch bolt 13. This latch bolt is of V-shape and comprises the latching arm 14 and the setting arm 15, the bolt being mounted on a pin 16 journaled at its ends in the flange wall 11 and the outer wall of the housing 12. The latch bolt has the inwardly extending arcuate abutment 17 which projects through the arcuate slot 18 in the wall 11.

The wedging structure for the latch bolt is shown as comprising outer and inner wedge members 19 and 20 having respectively the wedging wings 21 and 22 whose outer inclined edges are cooperable with the rear end of the latch bolt abutment 17. The outer wedging member has the upwardly and downwardly extending guide arms 23 and 24 respectively and the inner wedging member 22 has the upwardly and downwardly extending guide arms 25 and 26 respectively.

The wedging members are guided in a frame comprising the plate 27 having the upper front and back guide walls 28 and 29 deflected therefrom and secured to the flange wall 11, and the lower front and back guide walls 30 and 31 deflected therefrom and secured to the flange wall 11. As clearly shown on Figure 4, the front and back guide walls may be secured to the plate by the extension of ears 32 thereon through opening 33 in the flange wall 11. The upper front and back guide walls 28 and 29 receive between them the upper legs 23 and 25 of the outer and inner wedging member respectively, while the lower front and back guide walls 30 and 31 receive between them the lower arms 24 and 26 of the outer and inner wedging members respectively. Spiral springs 34 and 35 anchored

on the flange wall 11 engage against the upper ends of the outer and inner wedging members and tend to urge these members downwardly for engagement of the wedging members with the latch bolt abutment 17. A spring 36 anchored on the guide frame 27 engages a pin 37 on the abutment 17 and this spring tends to move the latch bolt to its unlatching or cocked position with the abutment 17 abutting the inner end of the slot 18. This cocked position of the latch bolt is shown on Figure 3, and in this cocked position the latch bolt abutment 17 will be below and engaged by the lower edges of the wedge member wings 21 and 22 so that the wedge members will be held in their upper positions against the force of the springs 34 and 35. When the door is moved to closed position and the housing 12 for the latch bolt enters and passes through the keeper K mounted on the door jamb, the setting leg 15 of the latch bolt will encounter the outer end of the latch abutment 38 on the keeper and the latch bolt will be rocked for engagement of its latching arm 14 with the inner end of the keeper abutment 38. As the latch bolt is rocked into latching engagement with the keeper, its abutment 17 is withdrawn from below the wedge wings of the wedging member and the springs 34 and 35 will then force the wedging members downwardly with their front wedging edges against the rear end of the abutment so that the latch bolt is further urged in latching direction to fully seat the door against the sealing material on the door frame.

Suitable means, such as that disclosed in my copending application herein before referred to, may be employed for releasing the wedging members from the latch bolt so that the door may be unlatched and opened. As shown, a roll-back 39 is mounted on the spindle 40 for a handle (not shown) on the door and this roll-back is engageable with a link 41 which is pivoted at 41' to one end of a releasing lever 42 pivoted intermediate its ends on the wall 10 as indicated at 43, the lever at its lower end having the abutment lip 44 below the outer wedging member 19 so that when the handle is turned and the lever 42 rocked, the abutment lip 44 will engage with the outer wedging member 19 for raising thereof. This outer wedging member at its lower end has an abutment lip 45 below the end of the inner wedging member and as the outer wedging member is raised, this lip will engage with the inner wedging member and both wedging members will be raised to their upper position for raising their wedging wings above the path of the latch bolt abutment 17 so that the spring 36 may restore the latch bolt to its unlatched or cocked position. Then upon release of the handle, the springs 34 and 35 will reset the wedging members for engagement of their wedging wings against the upper side of the latch bolt abutment so that this frictional and pressure engagement will tend to hold the latch bolt in its cocked position.

The drawing also shows a safety latch plate 46 in the guide frame 27 behind the wedging members, this safety latch plate having a tooth or projection 47 for entering a notch 48 in the latch bolt abutment 17 when the latch bolt is in its cocked position, a spring 49 yieldably holding the safety latch plate in this position. This safety latch bolt and its operation is fully disclosed and described in my copending application referred to. It has an extension 49 through the flange wall 11 and into the latch bolt housing 75

12 and when the door is swung toward closed position, this extension 49 encounters the lower wall of the keeper K and the safety latch bolt is raised to release the main latch bolt so that it may enter into latching engagement with the keeper. This safety latch bolt thus positively holds the latch bolt in its cocked position when the door is open and does not release it until the main latch bolt is about to enter into latching engagement with the keeper.

In the arrangement disclosed in my copending application referred to, the back edges of the wedging members would bear directly against the back guide walls 29 and 31 respectively on the guide frame 27, such bearing engagement being unyieldable. With such arrangement, when the latch bolt is latched and the wedging members are forced downwardly by their springs, the wedging pressure will force the wedging members transversely with considerable pressure engagement at their back edges against the back guide walls 29 and 31 and, as the vehicle travels and the door is jarred, and the wedging members are being forced downwardly by their springs, the wedging members themselves will become more or less wedged between the end of the latch bolt abutment and the back guide walls 29 and 31 of the guide frame 27 and the wedges will tend to stick so that considerable unnecessary exertion is required on the door handle or other releasing control for effecting release of the wedging members from the latch bolt abutment so that the latch bolt may be released for opening of the door. The main purpose of my invention is therefore to eliminate sticking of the wedging members without in anywise interfering with their proper wedging operation of the latch bolt. As shown on the drawing, a simple arrangement is to provide resilient backing for the wedge members, preferably in the form of springs. As shown, a bowed leaf spring 50 is interposed between the upper back guide wall 29 and the back edges of the wedging members, and a similar spring 51 is interposed between the back guide wall 31 and the back edges of the wedging members. These springs may be readily held in position by deflecting their ends 52 to extend across the upper and lower edges of the walls 29 and 31 respectively. With these resilient backings or cushions in the form of springs, the wedge members may yield slightly transversely as their wedging wings are forced into wedging engagement with the latch bolt abutment and wedging or sticking of the wedging members between the latch bolt abutment and the guide frame 27 will be eliminated. Furthermore, by the engagement of the back edges of the wedging members with the bowed backing springs, the friction will be materially reduced, the net result being that the wedge members may at all times be restored to their latch bolt releasing position by ordinary exertion on the door handle or other releasing controls. Furthermore, with my improved arrangement, the wedging members cannot cause the exertion of over pressure of the door against the door sealing strips which would tend to destroy the resiliency and sealing characteristics of the strips.

I thus provide simple and efficient means, in lock structure of the type described, for easing and cushioning the operation of the latch bolt wedging members so that such members may be released for door opening without undue exertion on the door handles or other controls. I do not, however, desire to be limited to the exact con-

struction, arrangement and operation shown and described as changes and modifications may be made without departing from the scope of the invention.

I claim as follows:

1. A vehicle door latching structure comprising a latch bolt for the door, for cooperation with a keeper, to be rocked to latching engagement when the door is swung toward closed position, a guide frame having longitudinally spaced abutment members, an elongated and longitudinally shiftable wedging member movable in said frame and having the back edge of its end portions disposed in opposed relation to said abutment members, said wedging member being arranged with its front edge of a portion thereof intermediate said end portions engageable laterally against said latch bolt for causing further rocking thereof for complete tight closure of the door, a spring engaging said wedging member to move it longitudinally into wedging engagement with said latch bolt, and spring means engaging said end portions of said wedging member and normally urging the back edge of said end portions into spaced relation to said abutments to oppose the tendency of said end portions to stick to the abutments consequent upon transverse movement of said wedging member moving into

wedging engagement and upon vibration of said member in service on a vehicle.

2. A vehicle door latching structure comprising a latch bolt for the door, for cooperation with a keeper, to be rocked to latching engagement when the door is swung toward closed position, a guide frame having longitudinally spaced abutment members, an elongated and longitudinally shiftable wedging member movable in said frame and having the back edge of its end portions disposed in opposed relation to said abutment members, said wedging member being arranged with its front edge of a portion thereof intermediate said end portions engageable laterally against said latch bolt for causing further rocking thereof for complete tight closure of the door, a spring engaging said wedging member to move it longitudinally into wedging engagement with said latch bolt, and springy metallic bearing members interposed between said abutments and the back edge of said end portions to normally urge the back edge into spaced relation to said abutments to oppose the tendency of said end portions to stick to the abutments consequent upon transverse movement of said wedging member moving into wedging engagement and upon vibration of said member in service on a vehicle.
